PAUL J. HUEBER, OF SYRACUSE, NEW YORK.

CONCRETE-BUILDING FORM.

1,421,236.

Specification of Letters Patent. Patented June 27, 1922.

Application filed July 6, 1920. Serial No. 394,195.

To all whom it may concern:

Be it known that I, PAUL J. HUEBER, of Syracuse, in the county of Onondaga, in the State of New York, have invented new and useful Improvements in Concrete-Building Forms, of which the following, taken in connection with the accompanying drawings, is a full, clear, and exact description.

This invention relates to temporary forms for concrete building structures and to the method of erecting the same, the main object being to provide a system of correlated form sections which may be easily and expeditiously erected or assembled in a secure manner for receiving plastic concrete for walls, columns, floors and various other parts during progressive building.

In other words, I have sought to provide a system of forms capable of being assembled in many different combinations for producing all-concrete buildings of widely varying designs.

Another object is to render the assembled form sections substantially self-sustaining during the process of erection and filling in of the concrete.

A further object is to enable the form sections to be easily and systematically removed and re-used in the construction of other concrete buildings without material loss from deterioration or breakage.

Other objects and uses relating to specific devices of certain form sections will be brought out in the following description.

In the drawings:

Figure —1— is a vertical sectional view of an assembly of certain form sections for a portion of a concrete building including one of the upright walls, two of the floors and one of the columns.

Figure —2— is a vertical sectional view through one of the walls taken on line 2—2, Figure —1—.

Figures —3—, —4—, and —5— are horizontal sectional views taken, respectively, in the planes of lines 3—3, 4—4, and 5—5, Figure —1—.

Figures —6—, —7— and —8— are perspective views of concrete separator blocks for the base plates, the interior wall plates and exterior wall plates, respectively, Fig-

ure —6— also showing the means for anchoring the separator block to the concrete footing course.

Figure —9— is a perspective view of one of the wedge plates of the floor form clamping means.

Figure —10— is a perspective view of one of the clamping bolts to be used in connection with the parts shown in Figures —8— 60 and —9—.

Figure —11— is a perspective view of one of the stud anchoring bolts.

Figure —12— is a side elevation and edge view of one of the eccentric levers adapted to cooperate with one of the clamping bolts for holding the intermediate and corner studs of the form in place.

Figure —13— is a detail sectional view of the stiffening frame and means for securing it to the inner form studs.

Figures —14— and —15— are perspective views of one of the clamping bolts and one of the separators for securing the corner studs and intermediate studs of the form in place.

Figure —16— is a vertical sectional view, partly in elevation, of a portion of the floor supporting forms and means for attaching them to the wall studs.

Figures —17— and —18— are, respectively, a side elevation and a face view of one of the beveled end pieces for one of the floor form joists.

Figure —19— is a detail sectional view of the means for supporting one of the floor form panels.

Figure —20— is an elevation of one of the interior metal faced studs showing its supporting plate in section.

Figure —21— is a face view of the parts shown in Figure —20—.

Figures —22— and —23— are face views at right angles to each other of one of the stiffening braces.

The method of erecting the forms for the various parts of the building, briefly stated, consists—

First, in laying a suitable concrete foundation or footing course to the desired level and permanently anchoring therein at predetermined intervals throughout the

length of the wall concrete spacing blocks which determine the thickness of the wall and spacing of the wall forms.

Second, mounting upon the upper face 5 of the footing course temporary footing strips or wall plates and bolting them to the opposite faces of the separator blocks.

Third, erecting temporary interior and 10 exterior wall studs and column forms and bolting them to footing strips or base plates in transversely spaced relation corresponding to the width of the spacing blocks.

Fourth, securing a temporary stiffening 15 frame to the upper portions of the several interior studs and bracing the column form to said studs.

Fifth, attaching temporary girder forms 20 to and between the studs and column forms, and

20 Sixth, placing the temporary wall and floor panels in operative position and securing them to their respective studs, girders and columns, after which the spacing blocks, wall studs, girders and 25 panels for the walls and floors may be continued indefinitely for successive stories with such alterations as may be necessary for modified details of construction; it being understood that the foregoing is intended only as a brief statement of the general 30 plan of erection of the forms and not as a specific method of assembly, which will be hereinafter more fully described.

Foundation.

35 In carrying out the objects stated, a concrete foundation or footing course —1— is first laid without forms in a trench, as —A—, which is made to the desired dimensions and extended under the entire wall 40 with its upper face substantially horizontal or level to receive and support the concrete superstructure and also the temporary forms therefor, as will be hereinafter more fully 45 described.

A series of previously formed concrete spacing blocks —2— (Fig. 6) are placed at suitable intervals along and upon the longitudinal centers of the upper faces of the 50 footing course —1— and are of considerably less width than that of the footing course, or substantially the same width as the width or transverse thickness of the concrete wall which is to be erected upon the footing 55 course, each spacing block having incorporated therein a U-shaped anchor bolt —a— having its opposite arms protruding below the lower face of the block, as shown in Fig. —6—, and embedded in the footing course 60 —1—, while the latter is in a more or less plastic state for firmly holding the block in a fixed and permanent position on the footing course, said block being also provided with a transverse bolt opening —a'— 65 for receiving a clamping bolt presently de-

scribed by which certain temporary form sections —3— are clamped in place.

These form sections —3— preferably consist of metal faced wooden strips running lengthwise of and upon the upper face of the footing course —1— and clamped against the opposite side faces of the blocks —2— by means of bolts —4— which are passed through the bolt opening —a'— in the blocks —2— and also through registering 75 apertures in the base plates or strips —3—, as shown more clearly in Figure —5—, each bolt having one end provided with a head for engaging the inner face of one of the strips, while the opposite end is provided 80 with a diametrical slot for receiving a wedge —5— for engaging the outer face of the opposite strip and thereby firmly locking the base plates or strips —3— to the separators preparatory to erecting other 85 form sections, it being understood that the bolt openings in the separator blocks —2— and form sections —3— are sufficiently large to permit the bolts —4— to be easily inserted and withdrawn when the locking 90 keys —5— are removed.

These base plates or strips —3— may be of any suitable length convenient for handling, but preferably terminate at one or the other of the spacing blocks —2— so that 95 their adjacent ends may be clamped against the spacing block by the same clamping bolt —4— and wedge —5—, the meeting ends of the sections —3— being rabbeted and beveled as shown in Fig. —5— to permit them 100 to overlap one upon the other and to be readily placed in operative position and removed when the bolts —4— are withdrawn, the overlapping ends of one or more sections serving also to assist to hold the 105 adjacent sections in place as shown more clearly in Figure —5—.

Additional clamping bolts —6— (Fig. 11) are inserted in registering openings in the opposite strips —3— some distance from 110 and between the bolts —4— or spacing blocks —2— for holding the lower ends of interior and exterior stud sections —8— in operative position upon the corresponding strips or base plates, as shown more clearly in Figures —20— and —21—, the inner ends of 115 said bolts —6— being provided with downwardly offset ends —6'— seated in recesses wholly within the adjacent faces of the strips —3—, while their opposite ends are slotted to receive wedge shaped keys —b— for engaging the adjacent faces of the studs —8— and strips —3—, as shown more clearly in Figures —20— and —21—, thereby firmly locking the studs to the strips. 120

The upper outer corners and upper inner corners of the exterior and interior strips —3—, respectively, are rabbeted longitudinally, and their upper faces beveled in opposite directions to receive the lower edges 130

of the stud sections —8— and —9— and suitable panel sections hereinafter described, said lower edges of the stud sections and panel sections being similarly rabbeted and 5 beveled to permit said sections to be easily removed and replaced from and upon their respective strips —3— when the locking keys —b— are removed, the lower edges of the studs being recessed to receive portions 10 of the bolts —6—, as shown more clearly in Figure —21— and are reinforced by a metal wearing plate —b'— for engagement by the key —b—.

In practice the interior footing plate —3— is preferably laid upon the upper face of the footing course —1— before the latter is set and before the spacing blocks —2— are placed in operative position so that the latter may be correctly aligned against the interior 15 plate lengthwise of the footing course in anchoring the same thereto, after which the exterior footing plate —3— is placed in operative position against the adjacent faces 20 of the spacing blocks.

25 The spacing blocks —2— determine the amount of separation or space, as —7—, between the wall studs and also between the wall panels hereinafter described, and, therefore, determine the thickness of the concrete 30 wall which is to be progressively erected between the wall studs and between the panels.

Wall studs.

I preferably employ one set of studs, as 35 —8— for the interior wall form and another set, as —9— for the exterior wall form; and in carrying these wall forms around the corners I preferably make use of special interior corner studs —10— and exterior corner studs —11—, the inner corners of the 40 interior studs being rabbeted and their edges beveled inwardly, while the outer corners of the exterior studs are rabbeted and their edges beveled outwardly for receiving 45 between them interior and exterior wall panels —12—, the edges of which are similarly rabbeted and beveled to permit them to be easily and quickly placed in operative position and removed or "stripped" when 50 their fastening devices hereinafter described are released.

As previously explained, the lower ends 55 of the studs —8—, —9—, —10— and —11— are rabbeted and beveled to seat snugly upon the upper rabbeted edges of their corresponding wall plates —3— where they are held in place by the bolts —4— and keys —5—, each stud being provided with a plurality of bolts —13— in spaced relation vertically for receiving nuts —14— and keys or buttons —15— which are rotatable upon their respective bolts —13— for clamping and releasing the adjacent edges of the panels —12— in and from their operative 60 positions.

These studs are preferably arranged in pairs, those of each pair being arranged opposite to each other and are held in parallel spaced relation near their upper ends by concrete spacing sleeves —16— (Figure 15) 70 extending across the intervening space —7—, and of substantially the same length or width as the spacing blocks —2—, each sleeve being provided with a central opening —c— of angular cross-section as shown more 75 clearly in Fig. —15— for receiving a bolt —17— of similar cross-section as shown in Fig. 14, said bolt having its opposite ends extending through registering openings in the studs of each pair and provided with 80 hook-shaped slots for receiving the pivotal pins of a pair of eccentric levers —18—, whereby when turned in one direction, their eccentric faces will engage the adjacent faces of the studs to hold them in operative position; or by releasing the levers they may be withdrawn from their slots in the ends of the bolt —17— to enable the studs to be removed.

The bolts —17— are provided with collars 90 —c'— rigid therewith for engaging the outer ends of the sleeves —16— and inner faces of the outer studs —11— and to thereby assist in holding the studs in properly spaced relation when the eccentric levers 95 —18— are tightened.

The bolt openings —c— in the sleeves —16— are sufficiently large to permit the bolt to be easily inserted therethrough and withdrawn, while the sleeves —16— are 100 adapted to be incorporated in the concrete during the progressive erection of the concrete wall between the interior and exterior forms and are provided with transverse peripheral grooves —d—, as shown in Figure 105 15, for receiving suitable reinforcing rods (not shown) for the concrete and holding said rods in place as the concrete work progresses.

The inner stud sections —8— for the outer 110 wall of the cellar or first story are preferably erected first or before the erection of the outer studs for the same wall, and extend from floor to ceiling, or from the footing strips —3— to the underside of the floor 115 forms hereinafter described, said stud sections being spaced a suitable distance apart along the footing course of each side of the building for receiving between them panel sections —12— of the form of such size as 120 may be conveniently handled, it being understood that after the lower ends of the inner stud sections of the outer wall have been secured in place to the footing strips —3—, they are properly plumbed, or 125 brought into parallelism and temporarily held in this relation by stiffening members —23— applied thereto near their upper ends to remain in place during the erection of the remaining sections of the outer wall of the 130

same story and concrete wall which may be progressively erected between the inner and outer form sections for the same wall.

Stiffener.

5 Each of the inner stud sections —8— of the outer wall form is provided near its upper end with a horizontally extending bolt —24— projecting inwardly some distance 10 beyond the inner face thereof for receiving and supporting the stiffening member —23—, which is preferably made of metal lumber such as sheet metal T-pieces arranged horizontally to lap one upon the other and 15 are held in place upon the inner end of the bolt —24— by wedges —25— passing through registering apertures in the overlapping portions and bolt as shown more clearly in Figure 13, the outer edges of the 20 stiffener —23— being spaced some distance apart from the inner faces of the stud sections to permit the inner panel sections to be placed in operative position and also to receive buttons —15— which are turnable 25 upon their respective bolts —24— to lock and release said panel sections in and from their operative positions.

This stiffening frame —23— may be made up of sections secured together end to end in 30 any well known manner so as to extend continuously across the inner faces of the upper ends of the inner stud sections —8— along the enclosing walls of the building, and thereby assist in holding said studs in fixed 35 relation, or in perpendicular parallelism against inward or lateral displacement preparatory to placing the floor forms for the next story as will be hereinafter more fully described, the buttons —15— being held in 40 place against axial displacement by nuts —14— similar to those previously described.

As illustrated, the bolts —24— are permanently secured to metal enclosing sleeves —24'— which are passed through apertures 45 in the stud sections and enlarged at their outer ends to prevent inward withdrawal while the inner ends are threaded and engaged by the nuts —14—, which, in turn, engage the inner faces of the buttons —15— 50 and serve to hold the bolts against outward displacement, or in fixed relation to their respective stud sections, the portions of the bolts just at the inside of the nuts —14— being provided with shoulders —26— 55 against which the adjacent faces of the stiffening frame —23— are adapted to abut although the keys —25— serve to additionally hold the stiffener against lateral displacement from the bolts in either direction.

60 It is, of course, understood that the corner stud sections —10— are also provided with bolts —24— similar to those previously described for the studs —8— for temporarily fastening them to the stiffener —23—, 65 and that these stud sections are of substan-

tially the same height as the sections —8— to cooperate therewith in forming supports for the floor forms hereinafter described, and also for receiving the inner panel sections —12— for the outer wall.

70

Floor forms.

If the area of the concrete floor to be constructed is sufficiently large to require concrete column supports and girders, it will, 75 of course, be necessary to provide forms for the columns and girders in addition to a suitable number of joist forms and panel sections, and for this purpose one or more concrete foundations or piers —1— are embedded in the earth where needed, as shown in Figure 1, each foundation pier being preferably located opposite one of the intermediate upright stud sections —8— of the outer wall form and is provided with a spacing 80 block —2— similar to that previously described for the footing course —1—, except that it will be made to conform to the cross-section form of the column, in this instance 85 square.

90 The form for the column consists of, in this instance 4, upright plates —19— arranged around the four sides of the separator —2— and supported at their lower ends upon separate sets of wedges —20—, 95 which also extend along the four sides of the separator for adjusting the plates —19— vertically as may be required to properly level up the girder forms carried by the upper ends of the plates —19—, said wedges 100 also serving to facilitate the removal of the plates and girders when stripping the forms as will be hereinafter more fully explained.

105 Two of the plates —19— of the column form opposite each other are shorter than the other, two to terminate against the lower edge of the girder form presently described, while the remaining two plates opposite each other extend upwardly to the top of the girder form and have their adjacent faces recessed 110 from their upper ends downwardly a distance corresponding approximately to the depth of the girder forms to form seats for the latter in addition to the seat formed by the upper ends of the shorter plates, said 115 plates for the column form being assembled to form liquid tight joints at the edges or corners, and may be temporarily held in this position by any suitable external clamping means so as to leave a clear open space between the plates of approximately the area 120 as the separator —2— for receiving the concrete to form the column.

125 The column form may be temporarily supported in an upright or plumb position by a brace —21— having one end attached to the upper portion of the column form and its opposite end attached to the lower portion of one of the stud sections —8— 130 directly opposite the column, the attaching

devices of said brace to both the column form and stud section preferably consisting of pins which may be readily inserted through apertured parts of the connected members and quickly removed when desired.

When the inner stud sections —8— and —10— of the outer wall forms and the upright plates —19— of the column form are erected in the manner described, the girder forms are next placed in position upon the upper ends of said stud sections and plates, each girder form consisting of a pair of opposed sheet metal channel plates —22— arranged endwise vertically with their channels facing each other and in spaced relation transversely for receiving and supporting a pair of inner wood sections —27— which are also arranged edge-wise vertically in transversely spaced relation against the inner faces of the channel sections —22— and are provided at their upper ends with out-turned flanges —28— resting upon the upper edges of said channel sections, the space between the lower edges of the wood sections being filled in by an additional wood plate —29— which is held in place by a button —15— similar to those previously described for holding the wall panels in place, except that these buttons are pivoted to the underside of the plate —29— to swing in a horizontal plane into and out of engagement with suitable keepers —30— on the lower edges of the channel plates —22— as shown more clearly in Figures 2 and 16.

As previously intimated, portions of the girder plates —22— rest upon seats on the inner faces of the longer plates —19— near the upper ends thereof, and are additionally held in place upon the column forms by clips —31— and keys —32— which are passed through registering apertures in clips and adjacent portions of the longer plates —19— as shown in Figure —16—.

The outer ends of the girder plates —22— are supported upon the upper end of one of the stud sections —8—, which is directly opposite the column forms and may be additionally held in place by clips on said stud section.

By assembling the parts of the girder in the manner shown forms a lengthwise channel therein open at the top and communicating with the space between the plates of the column form and also with the space between the inner and outer stud sections of the wall forms for receiving the concrete for the walls and girders.

The joist forms extend from opposite sides of the girder forms to the inner studs —8— of the outer wall forms at right angles to the girder and in parallel spaced relation corresponding to the spacing of said stud sections, each joist consisting preferably of

a pair of reversely arranged sheet metal T-⁶⁵ pieces —33—, or what is commonly known as metal lumber, having their vertical flanges overlapping and secured to each other and provided at suitable intervals with pendant bolts or threaded studs —34— for receiving buttons —15— and retaining nuts —14— therefor, the upper ends of the metal pieces —33— being capped by a wood strip or filler —35— as shown more clearly in Figure 19.

The metal strips of each joist form are secured at one end to the girder plates —22— by clips —31— and tapered pins —32— which are passed through registering apertures in the clips and adjacent end of the joist sections —33—. The other end of each of the joist sections —33— is supported edgewise upon the upper end of the adjacent stud section —8— and is clamped thereto by a tapered key —5— similar to that previously described for locking the lower ends of the studs to the footing strips —3—, except that it is passed through apertured lugs —37— and —38— on the adjacent portions of the metal section —33— and stud —8—, respectively, as shown in Figures 16 and 20.

The end of each joist form which is secured to one of the inner stud sections of the outer wall form is provided with a removable extension —36— having hook-shaped attaching members —39— for interlocking engagement with pins —40— on the sides of the metal sections —33—, the outer end face of the extension —36— being substantially coincident with the inner face of the adjacent stud when the joist form is assembled thereon to form a substantially unbroken surface along the inner face of said stud section from the footing course to the floor, while the upper face of the same extension is disposed in a horizontal plane substantially coincident with that of the upper face of the filling piece —35— and is adapted to overlap upon said filling piece and also upon the upper face of the adjacent end of the metal strip —33— to form a liquid tight joint therewith. The adjacent end faces of the main body of the strip —33— and extension —36— are beveled downwardly and outwardly, but are normally held together when the parts are assembled by hook-shaped members —39— on the extension —36— adapted to interlock with pins —40— on opposite sides of the adjacent end of the metal strip —33—, as shown more clearly in Figures 16, 17 and 18.

The only object in providing the joist form with a separable end section —36— is to enable these forms to be more easily stripped from the concrete after the latter is set.

It will be seen from the foregoing descrip-

tion that the floor forms are supported entirely by the column forms and inner stud sections —8— and —10— of the outer wall forms independently of the outer stud sections —9— and —11—, and that these inner stud sections —8— and —10—, together with the inner footing strips —3—, girder forms and joist forms constitute a skeleton frame for receiving and supporting the inner panels of the wall forms and also the panels of the floor forms.

The outer stud sections —9— and —11— of the outer wall form are preferably erected directly opposite the inner stud sections —8— and —10— after the latter have been installed and properly braced, and in fact the installation of these outer stud sections may be deferred until the floor forms are placed in operative position, and while it may be preferable to complete the erection of the forms for one story at a time, it is evident that the forms for the several stories, including the floor forms, may be erected before the concrete is poured into the intervening spaces.

Panel forms.

As previously intimated, the upper edge of the inner footing strip —3— and the upright edges of the inner stud sections —8— and —10— which face each other, are rabbeted and beveled inwardly to form stop flanges for limiting the inward movement of the panel sections —12— to approximately the vertical plane of the footing strip —3— and stud sections —8— so that the outer faces of those parts when assembled will lie in substantially the same vertical plane where they are held by turning the buttons —15— across the inner faces of the adjacent portions of the panels as shown more clearly in Figure 4.

These panel sections are preferably made up as units of such size as may be conveniently handled and preferably of a width corresponding to the distance between the stud sections, while the vertical height of each panel is equal to substantially half the height of the story from floor to ceiling, thus requiring in this instance two panels one upon the other to fill each space between the stud sections, the lower edge of the lowermost panel and upright side edges of both panels being also rabbeted and beveled to cause them to fit snugly against the corresponding rabbeted edges of the footing strip —3— and stud sections, and to thereby form substantially liquid tight joints. The adjacent meeting edges of both panel sections, which are arranged one upon the other, are also rabbeted and beveled for the same purpose and are held against inward displacement one upon the other by buttons —15— similar to those previously described. The

outer footing strip —3— and edges of the outer stud sections —9— and —11—, which face each other, are also rabbeted and beveled outwardly to receive panels —12— which are similar to the inner panels except that they extend above the level of the lower surface of the floor, but are preferably divided to form two panels for each space between the stud sections, the lower edge of the lowermost panel and upright edges of both outer panels being rabbeted and beveled to conform to the rabbeted and beveled edges of the outer footing strip —3— and outer stud sections and to form liquid tight joints therewith.

The meeting ends of the two panels for each space are also rabbeted and beveled and are held against outward displacement by buttons —15— similar to those previously described.

It is now evident that the inner panel sections may be removed inwardly from their operative positions, while the outer sections may be removed by outward displacement when stripping the forms.

The panel sections, as —40—, for the floor forms are of substantially the same area as the spaces between the joists and between the joist and outer walls, and are provided with substantially flat upper surfaces, the edges thereof adjacent the joists being supported by buttons —15— which are mounted upon the bolts —34— and held in place by the nuts —14—, as shown more clearly in Figure 19, in which they are shown as provided with ledges —41— extending under the adjacent edge of the filler strip —35— to form a liquid tight joint therewith, while the edges adjacent the outer walls are preferably supported upon the upper ends of the inner stud sections —8— and —10— and also upon the upper edges of the inner panel sections —12— being placed in position from below and held in place by the buttons —15—.

The edges of the floor panel sections adjacent the girders may be secured in any suitable manner to said girders to form liquid tight joints therewith.

The forms for the remaining stories may be successively erected in a manner which is practically a repetition of that previously described for the first story, except that the floor forms constitute a support for the spacing blocks —2— instead of the concrete footing course —1—. That is the concrete spacing blocks —2— are supported upon the upper flat faces of the floor forms for receiving and supporting inner footing strips —3— similar to those previously described as resting upon the concrete footing course —1— except that those for the outer walls are angular or L-shaped, as in Fig. 8, and have portions thereof extending upwardly to

determine the thickness of the wall, while other portions extend horizontally to determine the thickness of the floor.

The inner footing strips —3— rest upon the horizontally extending portions, under which conditions the outer panels for the outer wall may be built up continuously one upon the other to any height according to the number of stories.

10 The spacing blocks —2— for the partitions are preferably cross-shaped as shown in Figure 7 when the partitions are to be constructed along the lines of the girders so that portions of the spacing blocks extend 15 into the girder space, while the upwardly projected portions determine the thickness of the partition wall, the horizontal portions determining the thickness of the floor and correspond in thickness with the horizontally 20 extending portions of the spacing members —2— for the outer walls, and serve to support additional footing strips —3— for the partition forms.

These footing strips, like those previously 25 described as resting upon the footing course —1—, are secured to the separator blocks by bolts —4— and wedge keys —5—, which may be readily removed when stripping the forms. The partition forms are similar to 30 the outer wall forms in that they are composed of inner upright studs —8— and outer upright studs —9—, both of which are secured in transversely spaced relation to the footing strips —3— and rise to points in 35 proximity to the ceiling of the next floor for receiving and supporting intervening panels —12— similar to those previously described.

If beam ceilings are required, the joist —33— will simply be lowered with a corresponding lowering of the filler plates —35—, in which case the adjacent sides of the panel sections, as —40—, will be extended downwardly a corresponding distance to bring the ledges —41— against the underside of 45 said filler plates as shown at the upper floor of Figure —1—.

In stripping the various parts of the building form after the concrete for the walls, columns, floors and partitions have 50 set, the order of assembly of those parts will be reversed, the panel sections being first removed, then the floor sections, following which the stiffeners and braces, and then the stud forms and column forms may be removed, all of which may be re-used in the 55 erection of forms for other buildings.

What I claim is:

1. In a concrete building form, the combination of spaced upright posts and a panel 60 of substantially the same width as the distance between the posts, the inner and outer faces of the posts being disposed in substantially the same vertical planes as the corresponding faces of the adjacent portions of 65 the panels when the latter are placed in oper-

ative position, the adjacent edges of the posts and panels being flared outwardly to prevent the inward movement of the panels beyond said planes and to permit their free outward displacement from the posts. 70

2. In a form for concrete walls, the combination with a substantially horizontal footing course, of concrete spacing members of less width than the footing course anchored thereto in longitudinally spaced relation and provided with transverse bolt openings, bolts slideable endwise in said openings and extending some distance beyond the inner and outer faces of the spacing members, footing strips resting on the footing 75 course and against opposite longitudinal faces of the spacing members, and provided with openings for receiving the ends of the bolts, means on the ends of the bolts for holding the inner and outer footing strips 80 in place, upright studs attached at their lower ends to the footing strips in transverse alignment with the spacing members, additional concrete spacing members between the upper ends of each pair of stud forms 85 and provided with bolt openings, means passed through the openings in the upper spacing members for clamping the stud forms to the inner and outer faces thereof, panels inserted in the spaces between the 90 studs and turn-buttons on the studs movable into and out of engagement with the adjacent edges of the panels. 95

3. In a form for concrete walls, the combination with a footing course of inner and outer longitudinally extending footing strips 100 arranged in transversely spaced relation lengthwise of and upon the footing course and having their upper faces beveled, means for holding the strips in spaced relation, upright studs having their lower edges beveled and resting upon the beveled upper edges of said strips in spaced relation lengthwise thereof, means for holding the additional forms in transversely spaced relation, panels 105 inserted in the spaces between the studs, and turn-buttons pivotally mounted upon the outer faces of the studs and movable into and out of engagement with the outer faces of the adjacent edges of the panels. 110

4. In a concrete building form, the combination of a concrete footing course, a footing strip extending lengthwise of and upon said footing course and having its upper face beveled transversely, spaced upright 115 posts having their lower edges beveled to correspond with and resting upon the beveled upper edges of the footing strip, means for clamping the lower ends of the posts to the footing strips to hold their beveled 120 ends in contact with the beveled edge of the footing strip, and means for holding the upper ends of the studs in upright spaced relation. 125

5. In a concrete building form, the com- 130

bination of a footing course, a footing strip extending lengthwise of and upon the footing course, spaced upright posts having their lower ends resting upon the upper edges of 5 the footing strip, means for clamping the lower ends of the posts to the footing strip to hold them against relative movement, a girder supported upon the upper ends of the posts and constituting a part of the wall and 10 floor form, and horizontal floor joists secured to said girder.

6. In a concrete building form, the combination of a horizontal footing course, a footing strip extending lengthwise of and 15 upon the footing course, spaced upright posts having their lower edges resting upon the upper edge of the footing strip, the engaging edges of the posts and footing strip being beveled transversely, a clamping bolt 20 extending through registering openings in the footing strip and posts, a key engaging the bolt and extending across the outer sides of said beveled edges for locking the adjacent ends of the posts to the footing strip, 25 means for holding the upper ends of the posts in spaced relation, panels removably inserted in the space between the posts, and means for holding the panels in place.

7. In a concrete building form, the combination of a horizontally extending footing 30 course, a footing strip extending lengthwise of and upon the footing course, spaced upright posts having their lower ends resting upon the footing strip, means for clamping the posts to the footing strip, means for holding the upper ends of the posts in spaced 35 relation, clamping members permanently secured to the posts, panels in the spaces between the posts, and locking members engaging the clamping members and extending 40 across the meeting edges of the posts and panels.

8. In a concrete building form, the combination of a footing course, a footing strip 45 extending lengthwise of and upon the foot-

ing course, spaced upright posts having their lower ends resting upon the footing strip, means for clamping said posts to the footing strip, clamping bolts extending through openings in the posts transversely 50 of and above the footing course, tubular spacing members encircling portions of said clamping bolts and supported thereby above the footing course, panels between and abutting against the upright edges of the posts, 55 additional clamping bolts carried by the posts above the footing strip, and locking members on the last named clamping bolts extending across the meeting edges of the posts and panels.

9. In a concrete building form, the combination of a footing course, a footing strip extending lengthwise of and upon the footing course and having its upper edge beveled transversely, spaced upright posts having 60 their lower edges beveled to correspond with and resting upon the upper beveled edge of the footing strip, means for locking the lower ends of the posts to the footing strip, a girder supported by said posts and constituting a part of a concrete floor form, floor 65 form joists extending horizontally from and in the same plane as the girder, means for clamping the floor joists to the girder, clamping bolts secured to the posts, panels in the 70 spaces between the posts, locking members on the clamping bolts extending across the meeting edges of the posts and panels, floor panels inserted between the floor joists, and locking devices on the under sides of the 75 floor joists movable to and from a position across the meeting edges of the floor joists and panels.

In witness whereof I have hereunto set my hand this 19th day of June, 1920.

PAUL J. HUEBER.

Witnesses:

ROSE G. CARROLL,
H. E. CHASE.
